FEED LEG FOR ROCK DRILLS

Gustav C. Pearson, Denver, Colo., assignor to
 Gardner-Denver Company, Quincy, Ill., a corporation of Delaware

Application February 15, 1952, Serial No. 271,738

10 Claims. (Cl. 121—9)

1

My invention relates to improvements in rock drills and is more particularly directed to that type of drill commonly referred to as a "stoper" and the improvement deals especially with the means for holding the drill to its work.

The main object of the invention is to provide an extensible feed leg for drills of the type described wherein the length of the leg may be automatically extended as the drill progresses into the work.

Another object of the invention is to provide a feeding mechanism which might eliminate the usual blocking of the drill, decrease the distance between the end of the feeding mechanism and the face of the work. This is usually done by building a temporary blocking for the feed piston sufficiently to hold the drill in a proper relation to its work.

The invention particularly resides in the provision of a feed leg having an extension including a cylinder within which a piston operates, and the piston during certain periods of operation controlling movement in one direction of the extension cylinder.

Another object of the invention is to provide an extensible feed leg having a plurality of cylinders, one within the other and a piston within one, against which pressure impinges to hold the drill to its work, thus eliminating the disadvantages heretofore experienced with pistons of several diameters particularly a variance in the holding pressure for the drill.

Further objects of the invention will hereinafter appear, and to all of these ends the invention consists of the features of construction, arrangement of parts, and combination of elements, substantially as hereinafter fully described and claimed in the specification and shown in the accompanying drawings, in which:

Figure 1 is a vertical sectional view showing a rock drill having attached thereto the improved feeding mechanism.

Figure 2 is an enlarged sectional view of the feeding mechanism showing the respective elements in one position of their operation.

Figure 3 is a view similar to Figure 2 but showing the elements of the leg collapsed, prior to any outward movement, and

Figure 4 is a sectional view showing the position assumed by the extensible elements upon reaching the limits of their outward movements.

Briefly the invention presented herein is to provide a feeding means for maintaining a "stopper" drill in proper relation to its work without the necessity of temporary blocking.

2

The principal feature of the invention lies in the provision of a collapsible feed leg having a main cylinder, an extension cylinder and a piston one within the other, their combined operations being that the drill is first fed to its work by movement of the extension cylinder relative to the piston and then upon the extension cylinder reaching approximately the limit of its movement operating fluid is automatically directed against the extension cylinder in a reverse direction moving the same downwardly with respect to the main cylinder and piston until the piston assumes its furtherest innermost position within the extension cylinder, whereupon the extension cylinder again moves upwardly with respect to the piston, carrying with it, as a unit, the main cylinder and the drill connected thereto. Thus, it is apparent that movement of the drill to its work is accomplished solely by expansion of fluid between the adjacent faces of two piston heads, areas of like diameters, eliminating any variation in the fluid pressure holding the drill to its work.

Referring to the drawings in detail, the numeral 1 indicates a "stopper" drill having at its front end a drill steel 2 receiving blows from a reciprocating hammer 3, positioned within the cylinder of the drill.

The rear end of the drill proper carries the usual distributing valve and a backhead 4 to which the usual water and air connections are made for proper functioning of the drill, the latter being controlled by a suitable throttle valve positioned within the backhead.

The drill 1 is also provided with an outwardly extending handle 5 having at its outer end a manually operated valve 6, controlling the flow of operating pressure fluid active upon certain elements of the drill and feeding mechanism.

The backhead 4, at the rear of the drill 1, has positioned thereagainst an element 10, the lower edge of which is receivable within a collar 8, all being firmly retained to the drill by the usual side rods 7. The collar 8 is internally threaded receiving therein the end of a cylinder 9 into which projects a depending ring or skirt 11 formed upon the underface of the element 10 and provided with passages 37. The ring 11 surrounds a central port 40, the purpose of which will be clearly apparent as the description proceeds.

Positioned within the cylinder 9, and for movement longitudinally thereof, is an extension cylinder 12 having a piston head 13 which may be of any conventional type. The upper face of the head 13 is provided with a centrally disposed tubular projection 14, while its lower face has

a downwardly depending skirt 15 having an annular groove 16 adjacent a tapered portion 17, the purpose of which will be hereinafter more fully apparent. From the drawings it will be observed that the lower end of the cylinder 9 has fixed therein a bushing 41 forming a bearing and support for the cylinder 12 and at the same time serving as an abutment limiting its outward movement relative to the cylinder 9.

The free end of the cylinder 12 has fitted therein a bushing 18. Slidable within the bushing and the extension cylinder 12 is a piston 19 having at its upper end a conventional piston head 28 and at its lower end a tapered plug or pivot point 21.

Here again the piston head 20 is provided with a centrally tubular projection 22 partially closed by a cap 23 having positioned thereabout a spring clutch ring A for engagement with the tapered portion 17 and annular ring 16 carried by the piston head 13 of the cylinder 12, frictionally holding the cylinder 12 and piston 19 in a fixed relation to each other.

The tubular projection 14 of the piston head 13, is similarly provided with a cap 24 having a spring clutch ring B engageable with the inner face of the depending skirt 11 for frictionally holding the extension cylinder 12 in a fixed relation with respect to the cylinder 9.

Positioned within the tubular projection 14 and extending through the cap 24 is a tubular piston 26 normally held against the lower face of the element 10 by the spring 27. The purpose of this piston is to control the flow of operating fluid from the port 40 to the cylinders 9 and 12. Upon referring to Figures 1 and 3 it will be observed that the underface of the element 10, particularly that portion surrounding the port 40, is engageable by the end face of the tubular piston 26. When engaging the element 10, as shown in Figure 3, operating fluid is conducted from the port 40 through the piston 26 to the interior of the extension cylinder 12, moving the same upwardly relative to the piston 19.

Figure 2 of the drawing shows the cylinder 12 near the limit of its upward movement relative to the piston head 20, with its end bushing 18 slightly spaced therefrom. In such a position the button 31 of the rod 30, operating the tubular piston 26, is in contact with the underface of the piston head 20. Continued upward movement of the cylinder 12 will bring its bushing 18 in direct contact with the piston head 20 and at the same time the tubular piston 26 is held against upward movement with the cylinder 12, the result being that the end face of the piston 26 is withdrawn from engagement with the element 10. With such a relation of parts fluid is free to pass from the port 40 into the area surrounded by the depending skirt 11 and finally through the passages 37 formed therein to impinge upon the upper face of the piston 13, moving the extension cylinder 12 downwardly of the cylinder 9 and piston 19. At the same time fluid within the cylinder 12, between the piston heads 13 and 20, is forced therefrom through the tubular piston 26 into the cylinder 9, where it mingles with that entering the cylinder 9 through the passages 37, thus permitting full downward movement of the extension cylinder 12 with respect to the cylinder 9 and piston head 20. It will be noted from the drawings that the operation thus described is accomplished by means of the fact that the upper face of the piston 13, against which pressure fluid is active, is of a larger area than its underface.

The tubular piston 26 is provided adjacent its

lower end with openings 28 and a fixed plug 29 to which is connected a rod 30 extending approximately the full length of the extension cylinder 12, through the tubular projection 22 of the piston head 20, and having at its lower end a tapered button 31 adapted to be engaged during certain periods of operation by the underface of the piston head 20, maintaining the piston 26 immovable and out of contact with the element 10 upon any further upward movement of the extension cylinder 12, for the purpose herein before set forth.

From the foregoing description, it is quite apparent that normally the extension cylinder 12 is frictionally maintained inwardly of cylinder 9 by the ring B, and likewise the piston 19 is held inwardly of the cylinder 12 by the frictional engagement of the ring A with the depending skirt 15 carried by the piston 13 of the cylinder 12.

As previously pointed out, the holding handle 5 has at its free end a valve 6 which is in communication, through passageways 32, 33 and 34 with the feeding mechanism. The passageways 32, 33 and 34 serve to convey to the feed leg operating pressure fluid from the supply 35 and the throttle valve 36.

Let us now assume that a unit such as that illustrated in Figure 1 is ready to be placed in operation and it is being held vertically to drill overhead rock with its pivot point 21 resting upon the ground or a suitable support. In such a position it will be apparent that the drill steel 2 has not yet contacted the rock to be drilled.

In starting the unit the operator turns the throttle valve 36 permitting operating fluid, under pressure, to flow from the supply 35 to the distributing valve of the drill, setting the drill in operation, whereupon blows from the reciprocating hammer 3 will be transmitted to the steel 2. At the same time, operating fluid will pass from the throttle valve 36, through a passageway not shown, to a point midway of the drill where it enters the passageway 34 communicating with passageway 33 formed in the backhead 4. From the passageway 33 fluid flows through passageway 32, extending transversely of the element 10, leading to the port 40, the latter being surrounded by the end face of the tubular piston 26.

From the tubular piston 26 fluid passes out through openings 28 in its lower end and into extension cylinder 12, between the underface of its piston head 13 and the upper face of head 20 of piston 19. As the volume of fluid between piston heads 13 and 20 increases the extension cylinder 12 moves upwardly upon the piston 19 carrying with it the cylinder 9 and drill 1 until such time as the steel 2 contacts the face of the rock to be drilled. Further upward movement of the extension cylinder 12 is determined by the drilling progress of the steel into the rock.

Upward movement of the extension cylinder 12 is limited by engagement of its bushing 18 with the underface of the piston head 26. However, just prior to the extension cylinder 12 reaching the limit of its upward movement, the button 31, movable therewith, comes in contact with the underface of the piston 26, whereupon, any continued movement of the extension cylinder moves the element 10 and its port 40 away from the end face of the piston 26. When this action takes place, fluid is then permitted to pass from the port 40 into that area surrounded by the skirt 11, through the passages 37, where it then becomes active upon the upper face of the piston head 13 and the underface of the element 10.

Simultaneously with the passage of fluid

through the passages 37 to engage the upper face of the piston head 13, fluid from the extension cylinder 12 will pass through the tubular piston 26 to the interior of cylinder 9, mingling with that flowing through the passages 37. As the volume of fluid within the cylinder 9 increases and that within the extension cylinder 12 decreases, by reason of the difference in their piston areas, the extension cylinder will be moved downwardly with respect to the cylinder 9 and piston 19. Furthermore, due to the fact that neither the volume of fluid nor its pressure active upon the underface of the element 10 has varied, the drill and its steel will be maintained or held in its correct drilling relation with the rock. It will also be observed that by reason of the fact that the pivot point of the leg is immovable and the steel has been held in contact with the rock the overall length of the leg has neither increased or decreased during the downward movement of the extension cylinder 12.

This downward movement of the extension cylinder 12 continues until the underface of its head 13 comes in contact with the bushing 41 fixed in the end of cylinder 9. When this relation of elements occurs, fluid from the interior of the cylinder 9 passes through the tubular piston 26, port 28 to again impinge upon the underface of the piston head 13, thus again moving the extension cylinder 12 upwardly of the piston 19, and due to that fact that fluid between piston head 13 and element 10 is not compressible, the drill and steel will move in unison with the extension cylinder, determined by the penetration of the steel within the rock.

From the foregoing, it is apparent that I have provided common piston heads 13 and 20, the adjacent faces of which are of the same area, serving to move and maintain the drill and its steel to the work. Heretofore, in units designed for the same purpose it has been common to provide pistons of different areas the result being that neither the drill nor the steel is maintained properly against the work, causing a reduction in the work produced and a material loss in efficiency of the drill.

When it is desirable to retract the steel from the rock, the operator turns the hand valve 6 of the holding handle 5 so that an escape might be provided, through port 40, passageways 32, 33 and 34, for fluid active upon the element of the leg.

It is believed that the foregoing description covers fully and completely the important features of my invention and it will be quite apparent from the accompanying drawings that the drill will be maintained to its work by a constant and unvarying pressure solely upon the head 20 of the piston 19 and the adjacent face of the head 13. The only time that fluid pressure is active in cylinder 9 is when the extension cylinder 12 moves longitudinally thereof in a downward direction.

Unlike feed legs heretofore, the maintaining of the drill to its work is accomplished by elements of one diameter, thus maintaining a constant pressure upon the drill during its work. Commonly heretofore, where extension cylinders or additional pistons have been used to feed a drill, such has been accomplished by pistons of varying areas against which the fluid impinges. As an example, fluid may impinge upon the piston head of a cylinder corresponding to the extension cylinder 12 thus serving to hold the drill to its work and then at a later time when the piston 12 has assumed the full length of its movement, a second piston operates with a reduced area against which the

operating fluid impinges, thus reducing the pressure holding the drill to its work.

From the foregoing description, it is obvious that movement of the cylinder 12 with respect to the piston 19, and the main cylinder 9, is unrestricted when acted upon by fluid pressure. Any pressure that might accumulate within the cylinder 9 and the cylinder 12 during the movement of the elements is permitted to escape through suitable ports provided in the cylinder walls adjacent their ends.

From the foregoing, it is thought that the construction, operation and many advantages of the herein described invention will be apparent to those skilled in the art without further description, and it will be understood that various changes in the size, shape, proportion and minor details of construction may be resorted to without departing from the spirit or sacrificing any of the advantages of the invention.

What I claim is:

1. In a drilling mechanism, a rock drill, an expandable fluid operated feed leg holding the drill to its work, said leg including a pair of cylinders one within the other, a ground engaging piston within the inner cylinder, a throttle valve controlling the flow of fluid to one of the cylinders for the movement of both relative to the piston, means reversing the movement of the inner cylinder with respect to the other cylinder and piston, and said means operable when both cylinders assume a predetermined position relative to the piston.

2. In a drilling mechanism, a rock drill, an expandable fluid operated feed leg holding the drill to its work, said leg including a pair of telescopic cylinders, a piston within the inner cylinder supporting the leg and drill, a valve controlling the flow of fluid to the cylinders for the movement of both relative to the piston, means reversing the movement of one cylinder with respect to the other cylinder and piston, and said means operable when the reversible cylinder assumes a certain position relative to the piston.

3. In a drilling mechanism, a rock drill, a fluid actuated feed leg holding the drill to its work, said leg including a pair of cylinders one within the other, a piston within the inner cylinder supporting the leg and drill, a valve controlling the flow of fluid to the cylinders for moving both relative to the piston in the same direction at interrupted intervals, means reversing the movement of one cylinder prior to said intervals, and said means being operable when the reversible cylinder assumes a certain position during its initial movement relative to the piston.

4. A drilling unit comprising a rock drill and an expandable fluid operated feed leg holding the drill to its work, said leg having a pair of cylinders one movable within the other, a support engaging piston within one of said cylinders, the inner of said cylinders having two operative positions relative to the fixed cylinder, a valve admitting fluid to the cylinders for moving the same in unison relative to the piston in both operative positions of the inner cylinder, means controlled by the inner cylinder for moving the same from one operative position to the other, and said means operable upon certain relationship of the inner cylinder with the piston.

5. In a drilling unit, the combination of a rock drill and a fluid actuated feed leg holding the drill to its work, said leg including a cylinder fixed to the drill, an extension cylinder movable

relative to the fixed cylinder and serving to move fixed cylinder and drill when in each extremity of its movement, a support engaging piston within the extension cylinder, a valve admitting fluid to the cylinders moving the same in unison relative to the piston, means reversing the flow of fluid active upon the extension cylinder moving the same from the inner to the outer extremity of the fixed cylinder, and said means operable when the extension cylinder assumes a certain position relative to the piston.

6. In a drilling unit, the combination of a rock drill and a fluid actuated feed leg holding the drill to its work, said leg including a cylinder fixed to the drill, an extension cylinder movable within the fixed cylinder, a piston head formed on the inner end of the extension cylinder and movable from one end to the other of the fixed cylinder, a support engaging piston within the extension cylinder, a valve admitting fluid to the extension cylinder and against the underface of its piston head for moving the extension cylinder and drill relative to the supporting piston, means directing the flow of fluid to the upper face of the piston head for moving the extension cylinder in a reverse direction relative to the supporting piston, and said means operable when the extension cylinder assumes a certain position in its upward movement relative to the supporting piston.

7. In a drilling mechanism, a rock drill, a feed leg holding the drill to its work, said leg having a cylinder fixed to the drill, an extension cylinder within the fixed cylinder capable of assuming two operative positions therein, an abutment engaging piston within the extension cylinder, a valve admitting operating fluid to the extension cylinder moving the same relative to the piston, means carried by the extension cylinder reversing its direction of movement relative to the piston and fixed cylinder, and said means being operable upon the extension cylinder reaching a certain position during its first movement.

8. In a drilling unit comprising a rock drill and a fluid pressure actuated feed leg serving to hold

10
15
20

the drill to its work, said leg including a cylinder fixed to the drill, an extension cylinder movable within the fixed cylinder, a ground engaging piston within the extension cylinder, a piston head formed on the extension cylinder and assuming two functioning positions within the fixed cylinder, a throttle valve admitting fluid pressure between the two pistons for moving the drill to its work, and said pistons having like fluid pressure areas whereby the drill is uniformly held to its work at all times.

9. In a drilling mechanism, a rock drill, fluid actuated means holding the drill to its work, said means including a cylinder fixed to the drill, an abutment engaging element, a second cylinder movable relative to the first cylinder and element, a valve admitting fluid between the cylinders and element for moving the cylinders away from the element, and means controlled by the element whereby fluid moves the second cylinder reversely of the first cylinder and element prior to further movement of both cylinders relative to the element.

10. In a drilling mechanism, a rock drill, fluid actuated means holding the drill to its work, said means including a cylinder fixed to the drill, a cylinder movable relative to the fixed cylinder and capable of assuming two functioning positions with respect thereto, an immovable element over which the second cylinder is movable, a valve admitting fluid pressure to the cylinders moving both relative to the element from each assumed position of the second cylinder, and means controlled by the element regulating the flow of fluid moving the second cylinder from one functioning position to the other.
